UNITED STATES PATENT OFFICE

106,340

DESIGN FOR A DRESS

Vivian Amen, New York, N. Y.

Application August 2, 1937, Serial No. 70,796

Term of patent 3½ years

To all whom it may concern:

Be it known that I, Vivian Amen, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the dress disclosed of the panel on the front section which panel is broken at the neck and waistlines and is shirred into buckles as shown.

I claim:

The ornamental design for a dress, substantially as shown and described.

VIVIAN AMEN.
